UNITED STATES PATENT OFFICE.

FRED M. MCLEAN AND PHILLIP DROSS, OF MERIDIAN, MISSISSIPPI.

OPERATING MECHANISM FOR SKYLIGHT-COVERS, &c.

1,120,321.

Specification of Letters Patent.

Patented Dec. 8, 1914.

Application filed June 12, 1914. Serial No. 844,795.

To all whom it may concern:

Be it known that we, FRED M. MCLEAN and PHILLIP DROSS, citizens of the United States, residing at Meridian, in the county 5 of Lauderdale, State of Mississippi, have invented certain new and useful Improvements in Operating Mechanism for Skylight-Covers, &c.; and we do hereby declare the following to be a full, clear, and exact 10 description of the same, reference being had to the accompanying drawings, forming part of this specification, and to the figures and letters of reference marked thereon.

In modern building construction it is desirable 15 in many instances to provide relatively large openings for lighting and ventilating purposes, and this necessitates the employment of correspondingly large closures therefor.

It is the object of the present invention to provide a mechanism which may be operated by power for moving such closures into either their open or close position under the direct and immediate control of the attendant, whereby the range of movement may be accurately regulated and at the same time provision is made whereby the parts cannot be given an excess movement in either direction, such as would strain or break the operating mechanism or the closures themselves.

While the invention is primarily designed for operating skylight covers and will be described and illustrated in connection with such devices, it will be readily appreciated 35 that it is equally applicable to the movement of partitions or the covers of floor openings between the different stories of a building.

Referring to the accompanying drawings, Figure 1 is a sectional elevation somewhat diagrammatic in character, illustrating the application of the present invention for the operation of a pair of covers for a skylight or roof opening of a building. Fig. 2 is a perspective view of the arrangement 45 shown in Fig. 1, part of the operating mechanism being shown housed to protect the same from the elements. Fig. 3 is a top plan view of a portion of the operating mechanism illustrating the winding drum and motor gearing. Fig. 4 is a view of the three-point double throw control switch. Fig. 5 is a diagrammatic view of the switch connections with the motor.

Like letters of reference in the several 55 figures indicate the same parts.

In Figs. 1 and 2, the letter A indicates the

roof of a building in which roof there is a relatively large opening at B, the opening indicated being of such size as to practically throw open the entire top of the apartment below, thus exposing the whole apartment to light and air. For closing this opening two horizontally sliding covers C and C' are provided, said covers being adapted to travel on horizontal tracks or ways D, the number 60 of such tracks employed depending upon the size of the opening and covers. In the structure illustrated there are three tracks, one at each side and one along the center line of the opening and covers. Suitable 65 provision is made for preventing the entry of water around and between the covers such, for example, as the skirts c and the central interlocking weather strip c'.

For operating the covers a winding drum 70 E is provided with flexible cable connections intermediate said drum and the movable covers, there being reversely arranged cable connections for each cover, whereby the cover may be moved positively in either direction and by arranging the reversely arranged connections for both covers to be operated by the same drum, the covers will be moved simultaneously in opposite directions. In the preferred arrangement illustrated, a 75 flexible cable F' is attached at its opposite ends to one of the covers, as cover C', and extends in one direction over an idler pulley or sheave G', thence back over the center of the covers where it is guided by pulleys g', 80 thence to the winding drum and around the same a sufficient number of turns to prevent slipping, and thence back to the cover. One reach of the flexible connection passes over the covers and the other reach under the 85 covers, as shown in Fig. 1, suitable openings being provided in the edge walls of the covers for the purpose. The corresponding flexible cable F for the other cover C extends from the winding drum over the two covers 90 where it is guided by the sheaves g, thence around pulley or sheave G and back under the cover C' to the cover C where it is attached. The other reach of the cable F passes directly from the winding drum to 95 the lower portion of the cover C.

In adjusting the flexible cables for operation, it will be understood that the two reaches of each cable leave the drum from opposite sides and they are attached to the 100 covers in such relation that a rotation of the drum in one direction will bring the covers 105

- together with their meeting edges at the center of the roof opening, while a rotation of the drum in the opposite direction will move both of the covers to their full open position simultaneously, and obviously by arresting the rotation of the drum with the covers in any desired position, the size of the opening between the edges of the cover may be made of any width desired.
- 10 The power mechanism for operating the winding drum is preferably a reversible electric motor H which is connected through a train of gearing h , h' , h^2 , with the shaft of the winding drum, the ratio of the gearing being such that a relatively small motor may be employed for moving relatively large and heavy covers or slides. The motor illustrated is one having three-terminal or line connections i , i , i^2 , and for controlling the operating current these line connections extend to a switch mechanism embodying a three-pole double throw switch illustrated in Figs. 4 and 5. This switch consists essentially of an operated arm K having three- switch blades k projecting in opposite directions, and as shown in Fig. 5 adapted to be connected with the three-wire power line connections l , l , l . The blades of the switch are adapted for co-operation with usual spring contacts m to m^5 , respectively, and the spring contacts m , etc., are so connected with the motor terminals that when the switch is thrown fully in one direction current will be supplied for rotating the motor in one direction, and when fully thrown in the opposite direction, current will be supplied for operating the motor in the opposite direction. These motor connections are illustrated in Fig. 5 and further detail description is thought to be unnecessary for the purposes of the present invention.
- The motor with its winding drum and gearing is preferably inclosed in a housing N in Fig. 2 and the switch in a housing N', while the operating arm K of the switch projects out at one side in position for the attachment of a controlling cable or flexible connection O which latter is preferably an endless cable extending over pulleys down into the apartment and adapted for the application of operating handles O', whereby the cable may be pulled to throw the switch in either direction. Conveniently, the cable passes around a suitable idler or pulley S on the roof of the building beneath the edge of one of the sliding covers, this arrangement being adapted in order that provision may be made whereby the movement of the covers to their extreme positions in either direction 60 may be made to automatically shift the switch into its intermediate or neutral position, thus preventing any overrunning of the covers and insuring their being brought to rest, even should the attendant fail to throw the switch. This automatic control

is conveniently effected by providing the central cable with stops or knots P spaced apart a suitable distance and adapted for co-operation with an arm Q on one of the covers. The distance between the projections or knots on the controlling cable is such that one or the other will be engaged by the arm Q just before the cover reaches the extreme of its movement and the controlling cable will be moved thereby in a direction 75 to move the switch in its intermediate or neutral position with the blades out of engagement with the spring contacts, as shown for example by the full lines in Fig. 4.

The arrangement of the switch is such 80 that when brought to its neutral position by the movement of the cover it may be thrown to the opposite extreme by the manual manipulation of the control cable so as to reverse the direction of rotation of the motor 85 and cause the covers to travel in the opposite direction. This operation of the switch lever will be readily understood from Fig. 5 where it is shown in dotted lines as thrown in opposite directions. Suitable sheaves and 90 guides are provided for all of the cable connections so as to prevent undue wear on either the cable or the parts with which it is liable to contact.

In operation, assuming that the switch is 95 standing in its normal neutral position, it is a simple matter to open or close the covers by throwing the switch in one direction or the other. If the covers are closed the switch can only be thrown in a direction to 100 effect the rotation of the motor for opening the covers, and if they are fully opened it can only be thrown in a direction to close them, so that there is little or no liability of the operating mechanism being thrown out 105 of adjustment or broken by being set in motion in the wrong direction, and, inasmuch as a small motor with a spur gear train of reducing wheels is employed, the winding drum is caused to rotate slowly but with 110 considerable power for effecting the movement. This slow movement is desirable in order to prevent any possibility of damage by the momentum of the heavy covers, and owing to this construction the operating 115 mechanism lends itself favorably for moving any heavy covers or partitions such as it may be desirable to shift in or on a building.

Having thus described our invention, what we claim as new and desire to secure by Letters Patent, is,—

1. In building construction, the combination with a pair of oppositely movable closures and tracks on which said closures travel, of an operating mechanism embodying cables attached to and extending in opposite direction from each of said closures, guiding sheaves around which said cables pass, and a single winding drum around which the cables for both closures pass with 130

- the two reaches of each cable extending from the drum on opposite sides thereof, whereby the rotation of the drum in one direction will cause the closures to be moved simultaneously and positively toward each other and the rotation of the drum in the opposite direction will cause the closures to be moved simultaneously positively away from each other.
- 10 2. In building construction, the combination with a pair of oppositely movable closures and tracks on which said closures are guided and travel, of an operating mechanism for positively moving said closures into open or closed position embodying a winding drum and independent cables passing around said winding drum in opposite directions, the two reaches of each of said cables being connected with one of the closures, and guiding sheaves around which said cables pass whereby rotation of the drum will cause the closures to be moved simultaneously and positively in opposite directions and to an equal extent.
- 15 3. In building construction, the combination with oppositely movable closures and tracks on which said closures are guided and travel toward and from each other, of an operating mechanism for positively moving said closures embodying a winding drum, independent cables both passing around said winding drum but in opposite directions, the two ends of said cables being secured respectively to one of the closures and sheaves around which said cables pass whereby they are maintained taut and rotation of the winding drum will cause the closures to be moved positively and simultaneously in opposite directions in accordance with the rotation of the drum.
- 20 4. In a mechanism such as described, the combination with oppositely movable closures, of a winding drum, independent cables passing around said drum in opposite directions and having their two reaches connected respectively with the respective closures, whereby rotation of the drum will effect a simultaneous and positive movement of the closures in opposite directions, a motor, gearing intermediate said motor and winding drum, a switch controlling the direction of rotation of said motor, and operative connections intermediate one of the closures and switch for shifting the switch from an operative position to its neutral position controlled by the movement of the closure in either direction.
- 25 5. In an apparatus such as described, the combination with the oppositely movable closures, winding drum, flexible cables passing around said winding drum in opposite directions and having their two reaches connected respectively with the respective closures, whereby rotation of the drum in either direction will effect the simultaneous movement of the closures in opposite directions, of a motor, gearing intermediate said motor and winding drum, a reversing switch controlling said motor, a flexible controlling cable connected with said switch and having hand pieces for operating the same, a bracket on one of the closures, and projections on said switch controlled cable with which said bracket coöperates to move the switch into neutral position during the final movement of the closures in each direction.
- 30 6. In an apparatus such as described, the combination with the oppositely movable closures, winding drum, flexible cables passing around said winding drum in opposite directions and having their two reaches connected respectively with the respective closures, whereby rotation of the drum in either direction will effect the simultaneous movement of the closures in opposite directions, of a motor, gearing intermediate said motor and winding drum, a reversing switch controlling said motor, a flexible controlling cable connected with said switch and having hand pieces for operating the same, a bracket on one of the closures, and projections on said switch controlled cable with which said bracket coöperates to move the switch into neutral position during the final movement of the closures in each direction.
- 35 7. In an apparatus such as described, the combination with the oppositely movable closures, winding drum, flexible cables passing around said winding drum in opposite directions and having their two reaches connected respectively with the respective closures, whereby rotation of the drum in either direction will effect the simultaneous movement of the closures in opposite directions, of a motor, gearing intermediate said motor and winding drum, a reversing switch controlling said motor, a flexible controlling cable connected with said switch and having hand pieces for operating the same, a bracket on one of the closures, and projections on said switch controlled cable with which said bracket coöperates to move the switch into neutral position during the final movement of the closures in each direction.
